UNITED STATES PATENT OFFICE.

CHARLES F. KADE, OF SHEBOYGAN, WISCONSIN.

ADJUSTABLE BRACKET.

No. 870,439.

Specification of Letters Patent.

Patented Nov. 5, 1907.

Application filed January 9, 1906. Serial No. 295,283.

To all whom it may concern:

Be it known that I, CHARLES F. KADE, a citizen of the United States, residing at Sheboygan, in the county of Sheboygan and State of Wisconsin, have invented new and useful Improvements in Adjustable Brackets, of which the following is a specification.

This invention relates to brackets, the object of the invention being to provide a device combining a bracket and a supporting rail with which the bracket 10 is connected and upon which it is adjustable up and down with the greatest possible ease, the connection between the bracket and the supporting base or rail being such that the bracket may be readily detached, removed or replaced or adjusted up and down without 15 the aid of tools or special fittings.

A further object of the invention is to provide a bracket which may be stamped out of sheet metal and easily bent or fashioned by means of dies into final shape, the result being a light, strong and perfectly 20 reliable and safe bracket.

With the above and other objects in view, the nature of which will more fully appear as the description proceeds, the invention consists in the novel construction, combination and arrangement of parts as herein- 25 after fully described, illustrated and claimed.

In the accompanying drawings, Figure 1 is a perspective view of the bracket. Fig. 1^a is a similar view of the supporting base or rail. Fig. 2 is a longitudinal section through the bracket and rail, showing the connection between said parts. Fig. 3 is a rear elevation of a portion of the supporting rail or base. Fig. 4 is a front elevation of the same, showing the bracket in cross-section, the section being taken on the line 4-4 of Fig. 2. Fig. 5 is a rear or inner end elevation of the bracket. Fig. 6 is a horizontal cross-section through the supporting base or rail. Fig. 7 is a perspective view of a bracket of slightly modified form, showing also the supporting rail or base. Fig. 8 is a vertical longitudinal section through the bracket and a portion 40 of the rail. Fig. 9 is a rear elevation of the rail showing the bracket of Figs. 7 and 8 associated therewith. Fig. 10 is a front elevation of the rail showing said bracket in cross-section, the section being taken on the line 10-10 of Fig. 8. Fig. 11 is a detail horizontal 45 section through the inner end portion shown in Figs. 7 and 8.

Like reference numerals designate corresponding parts in all the figures of the drawings.

The bracket arm is made out of a single piece of 50 sheet metal of suitable gage or thickness, which is bent upon a longitudinal line to provide what may be termed horizontal and vertical flanges 1 and 2, which are substantially at right angles to each other, the flange 1 forming the floor or horizontal supporting 55 part of the bracket while the flange 2 constitutes a brace.

The flanges 1 and 2, in the preferred embodiment of the invention, are substantially co-extensive in length and, while the flange or floor 1 is preferably of uniform width from end to end, the flange 2 is made gradually 60 wider as it approaches the rear inner end of the bracket arm, as shown in Figs. 1 and 2. The outer end portion of the flange 2 is rounded off as shown at 3, while the extremity of the flange 1 is turned upward to form a terminal stop lug 4. The inner end of the flange or 65 floor 1 is bent upward at right angles to form a retaining lug 5, which is adapted to be inserted in any one of a series of slots 6 in a vertically extending supporting rail or base 8.

The supporting rail 8 is of channel or double-flanged 70 construction, or in other words, said rail 8 is provided with parallel flanges 9 extending backward from its opposite longitudinal edges, as clearly shown in Figs. 1^a and 6, said flanges being adapted to bear against the wall or other vertical support and to hold the body 75 of the rail at a suitable distance from such wall or support to admit of the insertion and removal of the retaining lug 5 of the bracket arm. The rail 8 is provided with holes 11 at suitable points to receive suitable fasteners for anchoring said rail in place against a wall or 80 other vertical support. The slots 6 correspond in shape to the cross-sectional shape of the retaining lug 5, said slots extending transversely of the face of the rail 8 and being elongated horizontally to conform to the retaining lug and to receive said lug when the bracket arm is 85 tilted upward to a considerable angle, said bracket being thereafter lowered or moved downward to a horizontal position, whereupon the retaining lug 5 engages behind the supporting rail and prevents the disengagement of the bracket from the rail, as shown in Fig. 2. 90

At its inner end, the flange or brace 2 of the bracket arm is provided with one or more laterally projecting sustaining lugs 12 which project at right angles to said flange and are adapted to bear against the outer face of the supporting rail 8, the result being that the bracket 95 arm is sustained in the position at right angles to said rail in the manner clearly shown in Fig. 2.

In some cases it is desirable to make the inner end of the flange 2 of considerable width, and this may be done either by increasing the width of the flange 2 100 itself and forming the same integral with the remainder of the bracket, or the same result may be accomplished by employing a flange extension or additional piece 105 13, as shown in Figs. 1 and 2, in which case the sustaining lugs 12 may be formed on said additional piece 13, or extension, or one of said lugs may be formed on the flange 2, while another or others may be provided on the extension piece 13. In any case, the sustaining lugs 12 bear against the outer face of the supporting rail 8, while the retaining lug 5 bears against the inner face of 110 the same. The arrangement of the sustaining lugs just described, is illustrated in Figs. 4 and 5. The exten-

sion piece 13 may be riveted to the flange 2, as shown at 14, or secured thereto in any desired manner, the securing means being employed merely to connect the parts 2 and 13, no particular strain being placed upon such securing means.

By reference to Figs. 7 to 10, inclusive, it will be seen that one of the sustaining lugs 12 may be made of angular construction or provided with an inwardly extending lip 15 of the right size to accurately fit into one of the slots 6 of the supporting rail, the width of said lip being approximately equal to the length of the slot 6, so that when inserted therein, the lower part of the extended or widened inner end of the bracket base will be prevented from swinging or moving laterally. This is not ordinarily necessary, however, as the shape of the retaining lug 5 will prevent such swinging of the bracket by reason of the close fit between said retaining lug and the slotted supporting rail. It is also within the scope of this invention to provide the extreme inner vertical edge of the flange 2 of the bracket with a small off-set lateral extension 16 to project across and bear against the corresponding inner vertical edge of the extension piece 13, said arrangement serving to brace the parts 2 and 13 relatively to each other and thereby adding to the stability of the bracket as a whole. The extension piece 13 may, as above indicated, be entirely omitted and the width of the flange 2 varied to suit. By employing the extension piece 13, however, bracket arms

of varying lengths may be used in connection therewith without changing the size, proportions or shape of such extension-piece. The bracket arm may, of course, be made of any desired length, and the general dimensions thereof may be varied without departing from the principle or sacrificing any of the advantages of the invention.

35

Having thus described the invention, I claim:

1. A metal bracket comprising a horizontal flange, and a vertical flange extending from one side of said horizontal flange, an upturned lug at the inner end of said horizontal flange, and laterally extending sustaining lugs 40 formed on the vertical flange, and a supporting rail provided with horizontal slots for engagement of the upturned lug and providing a bearing face for the laterally extended sustaining lugs.

2. A sheet metal bracket comprising a horizontal flange, a vertical flange extending from one side of said horizontal flange, an upturned lug at the inner end of said horizontal flange, an extension piece secured to said vertical flange, a sustaining lug formed on said extension piece and extending laterally therefrom, a supporting rail provided with horizontal slots and intermediate cross bars, and a lip extending at right angles to said sustaining lug.

In testimony whereof, I affix my signature in presence of two witnesses.

CHARLES F. KADE.
